UNITED STATES PATENT OFFICE.

SAMUEL N. HALL, OF HOUSTON, TEXAS.

PIPE-WRENCH.

1,107,937.

Specification of Letters Patent. Patented Aug. 18, 1914.

Application filed September 15, 1913. Serial No. 789,835.

To all whom it may concern:

Be it known that I, SAMUEL N. HALL, a citizen of the United States, residing at Houston, in the county of Harris and State of Texas, have invented certain new and useful Improvements in Pipe-Wrenches, of which the following is a specification.

This invention relates to new and useful improvements in pipe wrenches, and has particular relation to wrenches of the chain type.

The object of the invention is to provide a double acting wrench whereby a section of pipe may be turned in either direction, said wrench being provided with detachable jaws which may be readily removed when worn out and replaced with new ones.

Another object of the invention is to provide a wrench of the character described which is specially adapted to be used in screwing and unscrewing collars and other narrow pipe fittings.

A further feature of the invention resides in the novel arrangement and method of attaching the jaws to the handle.

A still further feature of the invention embodies a grip chain and the method of securing the same around the section of pipe to be turned.

With the above and other objects in view, the invention has particular relation to certain novel features of construction, operation and arrangement of parts, an example of which is given in this specification and illustrated in the accompanying drawings, wherein—

Figure 1 is a side elevation of the wrench, as applied to a pipe section. Fig. 2 is a plan view thereof, showing the wrench handle broken away. Fig. 3 is a front end view thereof. Fig. 4 is a rear view thereof, the handle being shown in section. Fig. 5 is a sectional view of a modified form showing one method of securing the rear grip paw to the handle, and Fig. 6 illustrates the wrench as applied to pipe fittings.

Referring now more particularly to the drawings, wherein like numerals of reference designate similar parts in each of the figures, the numeral 1 refers to the wrench handle which is preferably formed of steel or some other strong material and is of a size at its inner end to be readily grasped and gradually enlarges toward the other end. The enlarged or operative end of the handle has two hooks 2, 2 projecting rearwardly

therefrom between which is the slot 3, the purpose of which will be hereinafter set forth. The front of the operative end of the handle has a groove 4 and a jaw 5 is provided whose rear side has a tongue 6 which fits in said groove. In the form shown in Fig. 1 this jaw is held against lengthwise movement by the dowel pin 7 and is secured to the handle by means of the bolt 8. However, as shown in Fig. 5 the groove 4 may be dove-tailed and the tongue 6 correspondingly shaped and the jaw 5 locked against lengthwise movement by means of a key 9 which passes through alined orifices in the handle and also through the tongue 6. Any preferred method may be employed to secure said jaw to the handle but the methods shown will usually be found preferable. The free side of the jaw 5 is arcuate and toothed so as to readily engage with the pipe to be turned thereby.

Secured upon each side of the operative end of the handle are two jaws 10, 10. These jaws are secured to the handle by means of the bolt 11, which passes through said jaws and through the handle. The outer end of the handle is shouldered down on each side, forming the shoulders 12, 12 against which the inner ends of the jaws 10, 10, respectively, rest and the portions of said jaws which project beyond the end of said handle are thickened, thus forming the shoulders 13, 13, which are carried by the jaws 10 and against which the end of the handle 1 abuts. The jaws 10 are thus locked by said shoulders against turning relative to the handle. The forward or projecting ends of the jaws 10 are toothed so as to engage with the pipe to be turned thereby. A grip chain 14 is provided, one end of which is attached to the enlarged end of the handle. This chain is of the type ordinarily employed in devices of this kind, wherein the pintels 15 project past the side plates 16, which construction adapts the chain to fit into the slot 3 between the hooks 2 while the ends of the pintles project out laterally a sufficient distance to engage the inner sides of said hooks. The chain 14 is thus secured around the pipe and when the pipe section is to be turned in one direction, the jaw 5 will be employed and when it is to be turned in the other direction the wrench may be shifted so that the jaws 10 may be brought into engagement with the pipe without releasing the grip chain. Interme-

diate the jaws 5 and 10 is a recess 17, affording a sufficient clearance to permit this transfer of the pipe from one set of the teeth to the other without releasing the 5 chain, and permitting the slack in the chain for its release, when the pipe is placed in said central recess 17.

This form of wrench is specially adapted to be used in screwing pipe fittings and 10 collars and the like on to pipe sections. This use is illustrated in Fig. 6. Such fittings, as 15 18, are usually narrow and the jaws 10 are spaced too far apart to engage therewith. In screwing and unscrewing such fittings, 20 the jaw 5 may be employed and this jaw will readily engage with such collars or fittings however narrow they may be. This feature constitutes one of the chief features of this form of wrench, because the ordinary 25 pipe wrench now in common use cannot be used for such purposes. It is further to be noted that while I have shown the jaws 5 and 10 detachable either or all of them may be made integral with the handle by drop-forging and milling the jaws to the desired 30 shape, or otherwise forming them by any approved method of casting or machining.

What I claim is:—

1. A wrench having a pair of jaws forwardly projecting from the end of the 35 handle, rigidly connected to the sides thereof and having their operating faces toothed, a jaw corresponding substantially in width and alined with the space between said jaws 40 secured to the handle at the rear thereof, a link embracing the rearmost jaw, a chain connected thereto, and means at the end of the handle to engage the chain when co-operating with either of the jaw members, as set forth.

2. A wrench having a pair of jaws forwardly projecting from the end of the

handle, rigidly connected to the sides thereof and having their operating faces toothed, a jaw corresponding substantially in width 45 and alined with the space between said jaws and secured to the handle at the rear of the jaws, a chain attached to said handle adjacent said jaw, and means at the end of the handle to engage the chain when co-operating 50 with either of the jaw members, as set forth.

3. A pipe wrench comprising a handle having a solid gripping member adjacent its operating end, a pair of spaced jaws having 55 their operating faces toothed forming a gripping surface of greater width than that of said gripping member and adapted to be secured to the operating end of said handle, a link embracing said gripping member, a 60 chain connected thereto, and means at the end of the handle for engaging the chain when co-operating with either of the jaw members, as set forth.

4. A pipe wrench comprising a handle 65 having a solid removable gripping member adjacent its operating end, a pair of spaced jaws forming a gripping surface of greater width than that of said gripping member and adapted to be secured to the operating 70 end of said handle, a link spanning said gripping member, a chain secured to said link, and means at the end of the handle for securing the chain between said spaced jaws when co-operating with either of said members, as set forth.

In testimony whereof I have signed my name to this specification in the presence of two subscribing witnesses.

SAMUEL N. HALL.
